DAWSON M. TAGGART, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,355,927.

Specification of Letters Patent.

Patented Oct. 19, 1920.

Application filed December 28, 1918. Serial No. 268,625.

To all whom it may concern:

Be it known that I, DAWSON M. TAGGART, a citizen of the United States, residing at East Orange, in the county of Essex, State 5 of New Jersey, have invented certain new and useful Improvements in Telephone-Exchange Systems, of which the following is a full, clear, concise, and exact description.

This invention relates to telephone 10 systems and more particularly to such systems in which connections are to be established between telephone lines terminating at a manual exchange and telephone lines terminating at an automatic exchange.

In such systems it is frequently the practice to employ trunk circuits which are accessible to selecting apparatus at the automatic exchange so that a call from a subscriber 20 whose line terminates thereat may be extended to the manual exchange.

In systems of this nature it is desirable to provide means whereby the restoration of the receiver at the subscriber's station associated with the automatic exchange will immediately release the selecting apparatus of the automatic exchange which may be associated with the trunk during the connection.

It is the object of the invention to provide 30 an improved signaling system in a trunk circuit of this nature interconnecting exchanges of this character.

To attain this object in accordance with a feature of the invention, means is provided 35 associated with a trunk circuit of this nature for momentarily varying the resistance in circuit with the releasing means of the selector upon the termination of the conversation by the subscriber whose line terminates at the automatic exchange, whereby 40 although the selectors associated with the trunk are immediately released, a busy condition of the trunk terminals is thereafter restored and is maintained until disconnection from the trunk is effected at the manual exchange.

This and other features of the invention, not specifically mentioned above, will clearly appear from the following specification and 50 the annexed drawing in which the figure shows diagrammatically one embodiment of the invention as applied to a trunk circuit interconnecting a manual and an automatic exchange.

55 In the drawings, the line circuit A is

shown as terminating at an automatic exchange X and adapted to be connected to the trunk circuit C extending to the manual exchange Y, by means of a selecting means B which may be of a step-by-step type involving known circuits, only sufficient portions thereof being shown to properly illustrate the invention. A cord circuit D of any usual type is provided at the manual exchange Y for connection with the trunk 60 circuit C. Preferably the apparatus shown at the left of the dotted line 2, 2 is located at the automatic exchange, while that at the right of such line is located at the manual exchange.

70 It is thought that the nature of the invention may be more fully comprehended from the following description of the operation of the system shown in the drawing.

Assuming that the subscriber associated 75 with the line circuit A terminating at exchange or central office X, desires to converse with a subscriber whose line (not shown) terminates at the exchange or central office Y, and by removing the receiver 80 has obtained connection with the selecting circuit B by means of a line switch or by any other suitable means. The selector B comprises in part a line relay 1, a slow-release relay 2, a release magnet 3, an off-normal contact 4, a cut-off relay 5, a switch arm 6, terminals 7, 8 and 9 for coöperation therewith, and wipers 10, 11 and 12 for extending the calling line to the selected 85 trunk circuit. Upon the connection of the 90 calling line with the selector B, relay 1 operates over a circuit established from battery, through the left-hand winding of relay 1, the middle normal contact of relay 5, one conductor of the line circuit A, 95 through the sub-station apparatus associated with such line, returning over the other conductor of the line, the upper normal contact of relay 5 and the right-hand winding of relay 1 to ground. Relay 2 also 100 operates over a circuit established from battery, through the winding of relay 2, and the alternate contact of relay 1, to ground.

The selecting means may then be operated 105 in the usual manner responsive to the actuation of the usual calling device 13 at the station associated with the line circuit A, slow-release relay 2 remaining operated during process, and the off-normal contact 4 closing at the first movement of the selector. 110

When the selection is completed, the switch arm 6 has passed over terminals 7 and 8 and rests upon terminal 9, and wipers 10, 11 and 12 are in contact with the terminals of trunk circuit C, which it is assumed is idle. Relay 5 operates over a circuit extending from battery, through the terminal 9, the switch arm 6, the winding of relay 5, and the alternate contact of relay 2, to ground, thereby disconnecting line relay 1 from the line conductors, connecting thereto the tip and ring conductors of trunk circuit C through the wipers 10 and 11, and at its lower normal contact opening the lead connected to the off-normal contact 4. Thereupon trunk line relay 14 operates over a circuit established from battery, through the right-hand winding of relay 14, the conductor of trunk circuit C connected with the wiper 11, the lower alternate contact of relay 5, the ring conductor of the line circuit A, the sub-station apparatus associated with such line, the tip conductor of the line, the upper alternate contact of relay 5, the wiper 10 and the conductor of the trunk circuit associated therewith, and the left-hand winding of relay 14, to ground. Slow-release relay 15 operates over a circuit established from battery, through the winding of relay 15 and the contact of relay 14, to ground, and causes the operation of control relay 16 over a circuit established from battery, through the winding of relay 16 and the contact of relay 15, to ground. The closure of the outer left-hand contact of relay 16 connects ground to the release trunk lead or control conductor 30 connected with the wiper 12, thereby establishing the usual busy condition of the test contact associated with the trunk circuit C. Relay 1 releases upon the opening of the upper and middle normal contacts of relay 5. Relay 2 thereupon releases to open the operating circuit of relay 5 and to prepare a circuit for the release magnet 3, but due to the slow release nature of relay 2, relay 16 operates prior to the complete release of relay 2. Therefore, relay 5 is maintained operated over a circuit established from battery, through the terminal 9, the switch arm 6, the winding of relay 5, the wiper 12 and the release trunk conductor in contact therewith, and the outer left-hand contact of relay 16, to ground. The closure of the inner left-hand contact of relay 16 operates slow release control relay 17 over a circuit extending from battery, through the right-hand winding of relay 17 and the inner left-hand contact of relay 16, to ground. The closure of the outer right-hand contact of relay 16 short-circuits the high resistance left-hand winding of relay 18 which is included with the low resistance right-hand winding of such relay and the retardation coil 19 in a bridge 65 across the tip and ring conductors of the

trunk circuit. The closure of the inner right-hand contact of relay 16 operates relay 20 over a circuit established from battery, through the winding of relay 20, the contact of relay 21, the tip conductor of the trunk circuit C, the inner right-hand contact of relay 16 and the normal contact of relay 18, to ground. Lamp 22 is thereupon lighted over a circuit extending from battery, through the contact of relay 20 and the lamp 22 to ground. 75

Upon observing the illumination of the lamp 22, the operator at exchange Y inserts plug 23 of cord circuit D into jack 24 of the trunk circuit C. The resistance of the bridge, including the retardation coil 19 and the right-hand winding of relay 18, is such that the supervisory relay 25 and trunk relay 18 are operated over a circuit extending from battery, through the winding of relay 25, the ring contacts of plug 23 and jack 24, the outer right-hand contact of relay 16, the right-hand winding of relay 18, the retardation coil 19, and the tip contacts of jack 24 and plug 23 to ground. Thereupon a circuit is completed from battery, through supervisory lamp 26 in parallel with the contact of relay 25 and the resistance 27, the resistance 28, the sleeve contacts of plug 23 and jack 24, and the winding of relay 21, to ground. Resistance 27 shunts lamp 26, thereby, in the usual manner, preventing the lighting of such lamp, and relay 21 operates to release relay 20, thereby extinguishing calling lamp 22. The actuation of the usual listening key 29 enables the operator at the exchange Y to converse with the calling subscriber, and after the number of the desired line is ascertained, the trunk circuit C may be connected to such called line (not shown) in the usual manner. 100

Upon the termination of the conversation, the subscriber associated with the line A in replacing the receiver releases relay 14, which in turn releases relays 15, 16 and 17. 110 After the release of relay 16 and before slow release relay 17 has completely released in response thereto, a circuit is momentarily established from battery, through the terminal 9, the switch arm 6, the winding of relay 5, the wiper 12 and the release conductor 30 of the trunk connected therewith, the high resistance left-hand winding of relay 17, and the alternate contact of relay 18 to ground. The resistance of the left-hand winding of relay 17 is of sufficient value to cause the release of relay 5, thereby interrupting the continuity of the tip and ring conductors, reconnecting the line relay 1 to the selector and completing a circuit for the release magnet 3 extending from battery, through the winding of the release magnet 3, the off-normal contact 4 (now closed), the lower contact of relay 5, the normal contact of relay 2, and the normal contact of relay 130

1 to ground. Thereupon the selector B is disconnected from the trunk circuit C and is restored to normal condition in the usual manner. However, the complete release of 5 relay 17 short-circuits the high resistance left-hand winding thereof, thereby connecting the usual busy ground potential to the testing terminal of the trunk circuit at the automatic exchange through the alternate 10 contact of relay 18 and the normal contact of relay 17, thus effectively guarding the trunk against selection by any selector. Thus through the coöperation of the trunk line relay 14, slow release relay 15, control 15 relay 16 and slow-release control relay 17, the restoration of the receiver to the switch-hook at the station on line A, reduces the resistance of the control conductor 30 sufficiently to cause the release of the automatic 20 switching apparatus by means of which such line is connected with the trunk C, but a grounding potential is maintained to prevent the reselection of such trunk.

The opening of the outer right-hand contact of relay 16 removes the short circuit established around the left-hand high resistance winding of relay 18, whereupon the resistance of the bridge across the trunk conductors is increased sufficiently to cause 25 the release of supervisory relay 25 in the cord circuit B to light lamp 26 over a circuit established from battery, through the lamp 26, the resistance 28, the sleeve contacts of plug 23 and jack 24, and the winding of relay 21 to ground. The subsequent removal of plug 23 from jack 24 responsive to the disconnect signal restores all apparatus to normal.

It will be evident that with this invention 40 the possibility of the selector being unavailable for future use during the interval between the termination of the conversation by the subscriber whose line terminates at the automatic exchange and the disconnection 45 from the trunk circuit by the operator at the manual exchange, is eliminated without rendering the trunk circuit C selectable by other selectors during that period.

What is claimed is:

50 1. A telephone exchange system comprising a trunk circuit including a normally open control conductor terminating at a central office, a line circuit terminating at the office, a source of current, switching means controlled over the conductor for establishing connection between the line and trunk circuits for closing the control conductor and for connecting the source of current thereto, a link circuit at another central office for connection with the trunk circuit, and means responsive to the opening of the line circuit for reducing the current flow in the control conductor to a predetermined positive value.

2. A telephone exchange system comprising a trunk circuit including a normally open control conductor extending from a first to a second central office, a telephone line at the first office, a source of current, switching means controlled over the conductor for establishing connection between the line and the trunk circuit for closing the control conductor and for connecting the source of current thereto, a link circuit at the second central office for connection with the trunk circuit, means responsive to the opening of the telephone line for reducing the current flow in the control conductor to a predetermined positive value, and means responsive thereto for releasing the switching means to disconnect the line from the trunk circuit. 65 70 75 80

3. A telephone exchange system comprising a trunk circuit including a normally open control conductor extending from a first to a second central office, a telephone line at the first office, a source of current, switching means controlled over the conductor for establishing connection between the line and the trunk circuit and for closing the control conductor and for connecting the source of current thereto, a link circuit at the second central office for connection with the trunk circuit, and means responsive to a reduced current flow in the control conductor for releasing the switching means. 85 90 95

4. A telephone exchange system comprising a trunk circuit extending from a first to a second central office, a telephone line at the first office, switching means for connecting the line to the trunk circuit, a test terminal for the trunk circuit at the first office adapted to be connected to ground upon connection of the line with the trunk circuit, a link circuit at the second central office for connection with the trunk circuit, and means controlled by the contemporaneous connection of the link circuit and the line with the trunk circuit to maintain the ground connection of the test terminal independently of the continuance of the connection between the line and the trunk circuit. 100 105 110

5. A telephone exchange system comprising a trunk circuit including a normally open control conductor extending from a first to a second central office, a telephone line at the first office, a source of current, switching means controlled over the conductor for establishing connection between the line and the trunk circuit and for closing the control conductor, a link circuit at the second central office for connection with the trunk circuit, means responsive to the opening of the line for momentarily reducing the current flow in the control conductor to a predetermined positive value, and 115 120 125

means responsive thereto for releasing the switching means to disconnect the line from the trunk circuit.

6. A telephone exchange system comprising a trunk circuit including a normally open control conductor extending from a first to a second central office, a telephone line at the first office, a source of current, switching means controlled over the conductor for establishing connection between the line and the trunk circuit for closing the control conductor, and for connecting the source of current thereto, a link circuit at the second central office for connection with the trunk circuit, and a signaling device in the link circuit responsive to a reduced current flow in the control conductor.

7. A telephone exchange system comprising a trunk circuit including a normally open control conductor extending from a

first to a second central office, a telephone line at the first office, a source of current, switching means controlled over the conductor for establishing connection between the line and the trunk circuit and for closing the control conductor, a link circuit at the second office for connection with the trunk, a signaling device associated with the link circuit, and means responsive to the opening of the line for momentarily reducing the current flow in the control conductor to a predetermined positive value for releasing the switching means to disconnect the line from the trunk circuit and for operating the signaling device.

In witness whereof I hereunto subscribe my name this 27th day of December, A. D., 1918.

DAWSON M. TAGGART.
